Application April 16, 1952, Serial No. 282,658

10 Claims. (Cl. 315—169)

1

This invention relates to gaseous discharge tubes and more particularly to a novel gaseous discharge trigger switch of the glow transfer type.

The application of Richard K. Steinberg, Serial No. 192,199, filed October 26, 1950, and entitled "Glow Transfer Storage Device" describes a gaseous discharge tube of the glow transfer type wherein a single glow discharge is transferred from one cathode to another within the tube via glow transfer wires. Each glow transfer wire is physically attached to the cathode to which it is to transfer the glow discharge and has its other end extending into space between the anode common to all the cathodes and the cathode from which it is to transfer the glow discharge. The actual transfer of the glow discharge is effected by the preselected application of pulses to the cathodes which application is fully described therein. The cathode structure and principle of glow transfer described therein are equally applicable to this invention.

A principal object of the invention is to provide a gaseous discharge tube of the glow transfer type responsive to two inputs to produce two outputs.

Another object of the invention is to provide a gaseous discharge tube of the glow transfer type having one group of electrodes operative as a trigger circuit to produce a single output in response to a dual input and having other groups of switching electrodes arranged in glow transfer relation to the first group to produce a single output for each input applied to the tube.

Another object is to provide a gaseous tube of the glow transfer type which will provide an output at one output terminal which is a true representation of an input and an output at another output terminal which represents either the nine's or ten's complement of an input.

Still another object is to provide a gaseous discharge tube of the glow transfer type wherein two input and two output terminals are provided, input pulses to be counted are applied at one input terminal and pulses are applied to the other input terminal to provide an output at either of the output terminals.

A further object is to provide a gaseous discharge tube of the glow transfer type having first and second input terminals wherein the relative time occurrence and duration of the input pulses applied to the input terminals controls the number of output pulses appearing at the output terminals.

A still further object is to provide a gaseous discharge tube of the glow transfer type having

2

two input terminals and at least one output terminal wherein output producing pulses are applied to one input terminal and output control pulses are applied to the other input terminal, the relative duration of output control and output producing pulses occurring simultaneously determining whether none, one or a plurality of output pulses will be produced during that time interval.

Other objects of the invention will be pointed out in the following description and claims illustrated in the accompanying drawings, which disclose, by way of examples, the principle of the invention and the best mode, which has been contemplated, of applying that principle.

15 In the drawings:

Fig. 1 is a diagrammatic showing of one embodiment of the invention,

Fig. 1a shows the wave forms produced by the operation of the structure shown in Fig. 1,

20 Fig. 2 is a diagrammatic showing another embodiment of the invention, and

Fig. 2a shows the wave forms produced by the operation of the structure shown in Fig. 2.

Briefly, the invention comprises a gaseous discharge tube of the glow transfer type having a plurality of cathodes formed as open-ended cylinders and arranged in a preselected glow transfer relation by the employment of glow transfer wires. A single common anode is spaced equidistant from each of the cathodes. Only a single glow discharge exists within the tube at any one time and this glow discharge is transferred from one cathode to another in accordance with the input applied to the tube.

25 35 In one embodiment of the invention four cathodes are arranged in a closed glow transfer path and provide for glow transfer in one direction therearound. Two opposite or non-consecutive cathodes are each connected in glow transfer relation with another cathode glow transfer being provided for in either direction between these cathodes.

40 45 If a pulse is applied to a cathode in the closed glow transfer path it may effect a transfer of the glow discharge from the cathode where it exists to the opposite cathode. Hence, two pulses will transfer the glow discharge around the closed glow transfer path one time. It is seen, therefore, that these four cathodes function as a trigger. If a glow discharge exists at one of the cathodes connected in glow transfer relation with another cathode not part of the trigger, then a single pulse may effect a transfer of the glow discharge from one cathode to the other and back again. It is seen, therefore, that these two cathodes function as a switch, one of the cath-

odes also being part of the trigger. Output producing pulses are applied to an input terminal commonly connected to opposite cathodes of the trigger or to the other two switch cathodes. Output control pulses are applied to a second input terminal commonly connected to the other two cathodes of the trigger. An output is taken from each of the two switch cathodes not connected to an input terminal. The relative duration and time relationship of an output producing pulse to an output control pulse is employed to determine whether an output pulse will or will not result and if so at which output terminal it will appear and if two output pulses are produced one may be made to appear at each output terminal. Hence, the total number of output pulses appearing at one output terminal can be controlled to equal the number of output producing pulses applied to an input terminal or may be made to equal the nine's or ten's complement of the number of output pulses appearing at the other output terminal. Also the total number of output pulses can equal the number of input producing pulses plus an additional number dependent upon the number and type of control pulses employed.

Referring more particularly to Fig. 1 the gaseous tube trigger switch includes six hollow cathodes formed as open-ended cylinders and designated 10, 11, 12, 13, 14 and 15 respectively. The cathodes may be of the type described in the application above referred to. As described in that application, each cathode is equidistant from a common anode designated 16 herein and connected through an appropriate resistor 17 to a terminal 18 to which a suitable positive voltage is applied. Cathodes 10, 11, 13 and 14 are each connected through a suitable resistor to ground, while cathodes 12 and 15 are each connected through a suitable resistor to a voltage positive with respect to ground but less positive than the voltage applied to terminal 18. The entire electrode structure is included in any suitable gaseous atmosphere. Output terminals 10T and 14T are connected to the cathodes 10 and 14 respectively. Input terminal TP1 is connected to the cathodes 12 and 15 and input terminal TP2 is connected to the cathodes 11 and 13.

At any given time only a single glow discharge exists within the envelope of the gaseous tube. When input pulses are applied to the input terminals TP1 and TP2 a certain transfer of the existing glow discharge is effected. To effect this transfer certain glow transfer wires designated 10s, 11s, 11t, 12t, 13t, 13s, 14s and 15t are provided as shown. Each such wire has one free end extending intermediate a cathode and the anode 16 and its other end physically connected to another cathode. When a glow discharge exists between a cathode and the anode and a greater voltage difference is caused to exist between the anode and another cathode having a transfer wire attached thereto and extending intermediate the cathode to which the glow discharge exists and the anode than the voltage difference between the anode and the cathode to which the glow discharge exists, then that glow discharge will move along the glow transfer wire to exist in stable equilibrium between the cathode to which that wire is physically attached and the anode.

The operation of the novel gaseous trigger switch of the invention will be explained by joint reference to Figs. 1 and 1a. The pulses designated P1 and P2 respectively in Fig. 1a are applied to input terminals TP1 and TP2 respec-

tively shown in Fig. 1. These pulses may be obtained from any suitable or conventional source and the provision of such a source does not constitute a part of this invention.

In the initial or starting condition it is assumed that a glow discharge exists between the cathode 13 and the anode 16. The first pulse of P1 goes negative and the voltage difference between the anode 16 and the cathodes 12 and 15 is correspondingly increased. The transfer wire 15t is in the path of the glow discharge existing to the cathode 13 and the glow discharge therefore moves along the wire 15t to exist between the cathode 15 and the anode 16 so long as the first pulse of P1 remains negative.

Next, the first pulse of P1 goes positive. This causes the voltage difference between the cathode 11 and the anode 16 to be greater than that between the cathode 15 and the anode 16. Accordingly, the glow discharge is transferred along the transfer wire 11t to exist in stable equilibrium between the cathode 11 and the anode 16.

Next, P2 goes positive as indicated by pulse 1A to decrease the voltage difference between the cathode 11 to which the glow discharge exists and the anode. The glow discharge is therefore transferred along the transfer wire 10s to the cathode 10, since cathode 10 is at a lower potential than cathode 12. Hence, conduction to the cathode 10 causes the voltage thereat to increase as indicated by pulse 10T-1. When pulse 1A goes negative the voltage difference between cathode 11 and the anode is greater than that between cathode 10 and the anode and the glow discharge is transferred along the transfer wire 11s to exist between the anode and the cathode 11. The voltage at the output terminal 10T then decreases as indicated by pulse 10T-1.

This operation will continue so long as a P1 pulse does not occur. Hence, application of the pulses 2A, 3A and 4A to the terminal TP2 causes the pulses 10T-2, 10T-3 and 10T-4 respectively to appear at the output terminal 10T. It is seen that P2 might go negative and glow transfer still not be effected.

If P2 is positive, i. e. an A pulse exists, then the glow discharge exists between the cathode 10 and the anode 16. Glow transfer to the cathode 12 can occur only if a glow discharge is present at the cathode 11 immediately prior to the attempted transfer to the cathode 12.

It follows, therefore, that to effect such glow transfer P1 and P2 must be negative simultaneously. When such is the case the glow discharge transfers from the cathode 11 along glow transfer wire 12t to the cathode 12 and then when P1 goes positive the glow discharge transfers from the cathode 12 along the glow transfer wire 13t to the cathode 13.

Assume that the second negative P1 pulse is as indicated by the dotted lines. The glow discharge then exists between the cathode 11 and the anode 16 because the pulse 4A of P2 has just gone negative. The second pulse of P1 now goes negative and causes the glow discharge to transfer along transfer wire 12t to the cathode 12. This pulse then goes positive (during occurrence of 4B) and the glow discharge is transferred along the wire 13t to the cathode 13.

Next, 5A goes positive and the voltage difference between the cathode 13 and the anode 16 becomes less than that between the anode 16 and the cathode 14. Accordingly, the glow discharge is transferred along the transfer wire 14s to the cathode 14. The voltage at the cathode 14 is then

increased and the positive going portion of pulse 14C-5 appears at terminal 14T. When the pulse 5A goes negative the voltage difference between cathode 13 and the anode 16 becomes greater than that between the cathode 14 and the anode 16. The glow discharge is then transferred along the transfer wire 13s to the cathode 13. The subsequent pulses 6A, 7A, 8A, 9A and 10A cause a similar transfer of the glow discharge between the cathodes 13 and 14. At the end of the pulse 10A the glow discharge exists between the cathode 13 and the anode 16 as it was prior to the application of the first P1 pulse to the terminal TP1.

It should be noted that four pulses or a true indication appears at the output terminal 10T and six pulses or the ten's complement of the output at 10T appears at the output terminal 14T. Hence, by applying a single negative P1 pulse (the second as shown by the dotted lines) to the terminal TP1 while the terminal TP2 is negative the subsequent output at the terminal 14T is caused to represent the ten's complement of the output from the terminal 10T.

Assume that the second negative P1 pulse is indicated by the solid lines. Just prior to the occurrence of this pulse the glow discharge exists between the cathode 11 and the anode 16 as indicated by the existence of pulse 4B. When P1 goes negative the voltage difference between the cathode 12 and the anode 16 becomes greater than that between the cathode 11 and the anode 16 and the glow discharge is transferred along the transfer wire 12t to the cathode 12. Next, the pulse 5A goes positive and there is no transfer of the glow discharge since the voltage difference between the cathode 12 and the anode 16 remains greater than that between the cathode 13 and the anode 16. Pulse 5A then goes negative and again there is no transfer of the glow discharge because the voltage difference between the cathode 12 and anode 16 remains greater than that between the cathode 13 and the anode 16. The second pulse of P1 then goes positive and the voltage difference between the cathode 13 and anode 16 becomes greater than that between the cathode 12 and the anode 16. As a result the glow discharge is transferred along the transfer wire 13t to the cathode 13. Finally, pulse 6A goes positive and the voltage difference between the cathode 14 and the anode 16 becomes greater than that between the cathode 13 and anode 15. The glow discharge is then transferred via transfer wire 14s to the cathode 14 which exhibits an increased voltage as indicated by the positive going edge of pulse 14C-6. When the pulse 6A goes negative the voltage difference between the cathode 13 and the anode 16 is greater than that between the cathode 14 and the anode 16 and the glow discharge is transferred along the transfer wire 13s to the cathode 13 and the pulse 14C-6 has been provided at the output terminal 14T. Pulses 7A, 8A, 9A and 10A respectively cause a similar glow transfer to provide the corresponding pulses 14C-7, 14C-8, 14C-9 and 14C-10 at the output terminal 14.

It should be noted that the output pulses appearing at the output to determine 14T (pulses 14C-6 to 14C-10 inclusive) represent the nine's complement of the output pulses appearing at the output terminal 10T. Hence, by causing the second negative P1 pulse to span the time occurrence of one positive P2 pulse only the P1 pulse will effect glow transfer.

The tube structure shown in Fig. 2 is similar

to that shown in Fig. 1. In Fig. 2 the P1 pulses are again applied to the cathodes 12 and 15. However, outputs are taken from the output terminals 11T and 13T connected to the cathodes 11 and 13 respectively and the P2 pulses are applied to the cathodes 10 and 14.

Again, as in Fig. 1 at starting the glow discharge is assumed to exist between the cathode 13 and the anode 16.

When the first P1 pulse applied to the terminal TP1 goes negative it causes the voltage difference between the cathode 15 and the anode 16 to exceed that between the cathode 13 and anode 16 and the glow discharge is transferred over the glow transfer wire 15t to the cathode 15. When this pulse goes positive the voltage difference between the cathode 11 and the anode exceeds that between the cathode 15 and the anode and the glow discharge is transferred via transfer wire 11t to the cathode 11. The voltage at the cathode 11 then rises as indicated by positive going edge of the pulse 11T-1. As the glow discharge was transferred from the cathode 13 the voltage at terminal 13T decreased as indicated.

Each subsequent P2 pulse causes the glow discharge to be transferred from the cathode 11 to the cathode 10 and back again to the cathode 11. The negative going edge of the P1 pulse transfers the glow discharge from the cathode 11 to the cathode 10 and the positive going edge transfers it from the cathode 10 to the cathode 11.

A second negative P1 pulse is applied during the occurrence of the 3A pulse. When this negative pulse is applied the glow discharge is at the cathode 11 and is caused to be transferred via the glow transfer wire 12t to the cathode 12. Immediately, the voltage of the output terminal 11T decreases as indicated by the pulse 11T-4.

Next, the second P1 pulse goes positive and the glow discharge is transferred to the cathode 13. The voltage at the cathode 13 is increased as shown by the positive going edge of the pulse 13T-4. Finally, the pulse 3A goes negative and causes the glow discharge to transfer from the cathode 13 to the cathode 14. The voltage at the cathode 13 then decreases as indicated by the negative going edge of the pulse 13T-4 appearing at the output terminal 13T. Subsequently, each time P2 goes negative the glow discharge is transferred from the cathode 13 to the cathode 14 and each time it goes positive it is transferred from the cathode 14 to the cathode 13. This operation is continued until another negative P1 pulse is applied.

It is seen that for ten P2 input pulses that twelve output pulses were produced at the output terminals 11T and 13T. This increased pulse output is accomplished in Fig. 2 when a P1 pulse is applied during an occurrence of an A or positive pulse while in Fig. 1 the application of such a pulse during the occurrence of a B or negative pulse causes a number of output pulses to be produced identical in number to the number of input pulses.

It is readily seen from Fig. 2 that the application of additional similar P1 pulses during the occurrence of an A pulse will effect a further addition in the number of output pulses, each such pulse causing one additional output pulse to be produced.

From the above description, it is seen that in both Figs. 1 and 2 the cathodes 11, 12, 13 and 15 are operable as a trigger circuit to complete a cycle of operation in response to each two input pulses and that the cathodes 10 and 11 each col-

lectively serve as a switch to produce an output pulse in response to each input pulse applied thereto. Hence, if the cathodes 10 and 14 are omitted, the remaining cathodes 11, 12, 13 and 15 are operable as a trigger circuit to produce one output pulse in response to each single input pulse applied to the terminal TP1. This output pulse may be derived from any one of the cathodes.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. A gaseous discharge tube of the glow transfer type including a trigger section comprising first, second, third and fourth cathodes arranged in a closed glow transfer path to effect glow transfer therewith in only one direction; a fifth cathode arranged in glow transfer relation to said first cathode to form a first switch section so that a glow discharge is transferable from said first cathode to said fifth cathode and vice versa; a sixth cathode arranged in glow transfer relation to said third cathode to form a second switch section so that a glow discharge is transferable from said first cathode to said sixth cathode and vice versa; an anode common to each of said cathodes; a first common input connection to said second and fourth cathodes to effect glow transfer around said path in response to each two pulses applied to said connection; a second common input connection to said first and second switch sections to effect glow transfer from said one cathode thereof to the other cathode and back again in response to the application of each pulse applied over said second common connection, said glow transfer always being effected in one switch section as determined by the position of the glow discharge just prior to the application of the pulse; and an output connection from each switch section to convey an output therefrom.

2. A gaseous discharge tube of the glow transfer type including a plurality of cathodes coupled in glow transfer relation to form a closed glow transfer path; first means connected to apply a predetermined number of successive pulses to said cathodes to cause said glow discharge to traverse said path in one direction in a step-by-step fashion; cathode switch means each including an additional cathode arranged in glow transfer relation to a selected one of said plurality of cathodes; and pulse input means connected to apply a pulse to said switch means to transfer a glow discharge from said selected one of said plurality of cathodes to said additional cathode and back again.

3. The gaseous discharge tube set forth in claim 2 wherein four cathodes form said closed glow transfer path and the first and third cathodes thereof are included in said switch means.

4. The gaseous discharge tube set forth in claim 3 wherein said first means is connected to said second and fourth cathodes and said pulse input means is commonly connected to said first and fourth cathodes; and an output connection is provided to each of said two additional cathodes.

5. The gaseous discharge tube set forth in claim

3 wherein said first means is connected to said second and fourth cathodes and said input means is commonly connected to said additional cathodes; and an output connection is provided to said first and third cathodes.

5. A trigger switch of the gaseous discharge glow transfer type wherein a group of six cathodes are employed to provide a single gaseous discharge tube having a trigger section provided with a closed glow transfer path and two switch sections provided with a closed glow transfer path; glow transfer means intermediate successive ones of four of said cathodes to form said trigger section; and glow transfer means intermediate two different ones of said four cathodes and different ones of the two remaining cathodes to form two switch sections.

10. A trigger switch of the gaseous discharge glow transfer type wherein a group of six cathodes are employed to provide a single gaseous discharge tube having a trigger section provided with a closed glow transfer path and two switch sections provided with a closed glow transfer path; glow transfer means intermediate successive ones of four of said cathodes to form said trigger section; an anode common to each of said cathodes and voltage means for establishing a glow discharge between said anode and a pre-selected one of said cathodes; first pulse input means connected to said trigger section for applying pulses thereto to effect a transfer of said glow discharge along said closed glow transfer path in a step-by-step fashion; second pulse input means connected to said switch sections for applying timed pulses thereto to effect preselected glow transfer to the cathodes thereof; an output connection to at least one of said switch sections for supplying a number of pulses dependent upon the number of pulses applied from said first 15 and second pulse input means and the relative duration and time occurrence of the pulses from said first and second means.

15. The invention set forth in claim 7 wherein an output connection is provided to each of the said switch sections so that the number of pulses supplied to each output is dependent upon the number of pulses applied to said switch section intermediate each pulse applied to said trigger section.

20. A trigger switch of the gaseous discharge glow transfer type wherein a group of six cathodes are employed to provide a single gaseous discharge tube having a trigger section provided with a closed glow transfer path and two switch sections provided with a closed glow transfer path; glow transfer means intermediate successive ones of four of said cathodes to form said trigger section; an anode common to each of said cathodes and voltage means for establishing a glow discharge between said anode and one of said cathodes common to the trigger section and a switch section; first input pulse means connected to said one cathode of said trigger section and the cathode one removed therefrom 25 along said closed path to effect glow transfer from either of said cathodes to the other cathode of that switch section and back again in response to each pulse applied thereto; second pulse input means connected to the two remaining cathodes 30 of said trigger section to advance said glow discharge from the cathode common to said trigger section and one switch section to the other cathode common to said trigger section and the other switch section in response to each pulse; output connections from each of said two remaining

cathodes so that the combined output is equal to one less than the number of pulses applied from said first pulse means and the number of pulses supplied by each output connection is the nine's complement of the number supplied to the other.

10. In a gaseous discharge tube of the glow transfer type; four glow transfer cathodes arranged to form a single closed glow transfer path and operable as a trigger circuit; a switch circuit comprising two cathodes, one common to said trigger circuit arranged to form a single closed

glow transfer path; an anode common to said cathode; voltage means for establishing a glow discharge between only one of said cathodes and said anode; pulse means connected to apply discrete pulses to said trigger circuit and said switch; and output means connected to said switch to derive a preselected pulse output therefrom.
